Dec. 164

Elihu Smith, Albany, N. Y.
Letters Patent No 164 dated 18th January 1848

The Schedule referred to in these Letters Patent
and making part of the same.

To all whom it may concern:

Be it known that I, Elihu Smith of
the City and County of Albany in the State of New York have invented
a new and improved design for the stove plates of a stove (called, to
distinguish it, the Capitol) of which the following is an exact descrip-
tion. The design or ornament is on the exterior surface of the side
and top plates of the stove and may be seen in the annexed drawings.
Figs. 1 and 2. In Fig. 1, the side plate is ornamented with an inter-
twisted vine with leaves and clusters as seen at C. The smaller door
has a branching ornament as seen at B, and the larger door is or-
namented with an upright flower from which proceed branching stems
and from the lower part of which runs a vine as seen at A. The
top plates of the stoves are each ornamented with an edging around
the upper surface of the same as seen at F. F. F. and at G. G.
in the same Fig. 1. The side plates of the upper oven, one of which
is seen at C, are ornamented with two panels, with wrought borders,
enclosing each an ornamented vase with upright and branching
stems as seen at C.

In Fig. 2, the door of the stove
oven is seen at D, which has for an ornament a similar vase with
a tapering plant in it and curved branches.

What I claim as my invention and desire to secure by
Letters Patent is the design of the stove plates as above described.
